UNITED STATES PATENT OFFICE.

JOHN W. D. FIFIELD, OF NORTH BROOKFIELD, ASSIGNOR TO ALFRED H. BATCHELLER, OF BOSTON, MASSACHUSETTS.

LAST.

SPECIFICATION forming part of Letters Patent No. 288,984, dated November 20, 1883.

Application filed August 6, 1883. (No model.)

To all whom it may concern:

Be it known that I, JOHN W. D. FIFIELD, of North Brookfield, county of Worcester, State of Massachusetts, have invented an Improvement in Lasts, of which the following description, in connection with the accompanying drawings, is a specification, like letters on the drawings representing like parts.

This invention, relating to lasts, has for its object to hold the block in position in a novel manner, so that the same cannot possibly be moved backward longitudinally from the toe when the bottom of the last is uppermost and the shoe is being lasted or bottomed.

My invention consists, essentially, in the combination, with a last and its block, of a gravitating block-holder adapted to engage the block when the bottom of the last is uppermost and to release the block when the top of the last is uppermost.

Figure 1, in longitudinal section, represents a last, block-holder, and block embodying my invention. Fig. 2 shows the block detached. Fig. 3 shows two views of the block-holder; 25 and Fig. 4 is a longitudinal section of a last and block, showing a modification of my invention.

In the drawings, A represents a shell-like cast-metal last, having a socket, A', to receive the usual standard of a so-called "lasting or nailing jack." This last is provided with a metal block, B, having a tongue, b, to enter a recess formed in the last, the sides of the said block being, when the latter is in position, substantially flush with the sides of the last.

The block B, Figs. 1 and 2, made as a cast-metal shell, has a lug or projection, b², at its inner side at a little distance back from the large end 2 of the block. The block is placed 40 in position on the last when the bottom of the last is turned downward and while the block-holder c, pivoted at d on the last, occupies the dotted line position, Fig. 1; but as soon as the block B is placed in position the last, with the

upper thereon, is turned over, so that the bottom of the last is uppermost, when the block-holder c, by reason of gravity, drops from its dotted into its full line position, Fig. 1, causing the hooked part 3 of the said block-holder to fall behind the projection b² of the block B, 50 the block-holder engaging and retaining the block against accidental longitudinal movement backward from the toe of the last so long as the bottom of the last is uppermost.

To apply my invention to an ordinary 55 wooden last having a block, D, of usual shape, I provide the main part of the last with a hole, f, for the reception of a gravitating block-holder composed of a pin, g, having a heavy head, g', and I cover the mouth of the said 60 hole with a metal guide-piece, h, inserted therein, as in Fig. 4, attached to the last by screws 4, and having a central hole for the passage of the pin g.

The block B is provided with a hole, m, into 65 which the pin g drops when the last, the block having been applied in correct position, is turned to place its bottom uppermost.

I do not desire to limit my invention to the particular construction of gravitating block-holders herein shown, as it is obvious that the construction of the same may be variously modified without departing from my invention.

I claim—

As an improved article of manufacture, a last having a block and a gravitating block-holder, substantially as described, adapted to move by gravity alone to engage and hold the block in place, substantially as described. 75 80

In testimony whereof I have signed my name to this specification in the presence of two subscribing witnesses.

JOHN W. D. FIFIELD.
